UNITED STATES PATENT OFFICE.

FRANK D. WARD, OF NEW YORK, N. Y.

PROCESS FOR CONSTRUCTING CAR-WHEELS.

1,176,798.

Specification of Letters Patent. Patented Mar. 28, 1916.

Application filed July 13, 1911. Serial No. 638,376.

To all whom it may concern:

Be it known that I, FRANK D. WARD, a citizen of the United States, and a resident of the city of New York, borough of Manhattan, county and State of New York, have invented certain new and useful Improvements in Processes for Constructing Car-Wheels, of which the following is a full, clear, and exact description.

10 This invention relates to car wheels or like articles of cast steel, and has for its object the forming of such articles, according to which the web and hub are produced in a manner which permits them to retain 15 the natural properties of the metal, after which the rim as a separate casting is rolled thereon and compressed to any degree of hardness desired. This and other objects will appear fully hereinafter and be particularly pointed out in the claim.

20 The process of treating the metal is preferably in accordance with that described in my application filed July 13, 1911, Serial No. 638,377, while the machine used for rolling and compressing the rim on the spider is preferably similar to that which forms the subject matter of my application, filed June 22nd, 1911, Serial No. 634,757.

Reference is to be had to the accompanying drawings, which represent, merely as an example, a car wheel formed in accordance with the invention, and in which drawings—

Figure 1 is a side elevation of the wheel, and Fig. 2 is a vertical section on the line 2—2 of Fig. 1.

30 The web 1 and hub 2 together constituting the wheel-center are cast of steel or any other suitable metal. The mold is preferably of such a form as to give to the periphery of the web the peculiar cross sectional shape shown best in Fig. 2 and having the scallops or recesses 3 extending around the circumference, as indicated by dotted lines 35 in Fig. 1. The purpose of this form of casting is to prevent the rim from creeping on the web, as might be expected from the driving strains when the wheel is in use.

The web is treated in accordance with the process as outlined in the application above 50 mentioned, except that its periphery is not subjected to the rolling operation, as will appear hereinafter.

The rim 4 is cast in a suitable mold and after being removed from the "soaking pit" 55 while still hot and plastic is placed in position encircling the periphery of the web 1, the wheel center having previously been placed in position on the rolling machine described in the application hereinbefore referred to.

The rolling operation is carried on while the rim is hot and results in the compression of the rim and the forcing of the rim metal into the scallops 3, whereby a perfect and 65 secure union between the rim and web is effected.

As pointed out in my co-pending application Serial No. 638,377 the rolling of the rim also hardens and compresses the metal 70 of the rim.

The tempering of the wheel as described in my process application before referred to, is then proceeded with.

Having thus described my invention what 75 I claim as new and desire to secure by Letters Patent is:

The process of forming car wheels which consists in forming a rigid wheel center having a series of spaced recesses on its periphery, forming the rim or tread separately and applying the same to the wheel center while the rim is yet hot and plastic and rolling or compressing the rim on the wheel center whereby to simultaneously force portions 80 of the rim into the recesses, secure it in place 85 and harden and toughen the texture of the metal forming the rim.

In testimony whereof I have signed my name to this specification in the presence of 90 two subscribing witnesses.

FRANK D. WARD.

Witnesses:

MARTIN BOURKE,
WORTHINGTON CAMPBELL.
